US00D856298S

(12) **United States Design Patent** (10) **Patent No.:** **US D856,298 S**
(45) **Date of Patent:** **** Aug. 13, 2019**

(54) **TELECOMMUNICATIONS DEVICE**

(71) Applicant: **Dolby Laboratories Licensing Corporation**, San Francisco, CA (US)

(72) Inventors: **Andrew Border**, Los Altos, CA (US); **Christopher Bennett**, North Turramurra (AU); **Thao Hovanky**, San Francisco, CA (US); **David Clementson**, Palo Alto, CA (US); **Jeffrey William Smith**, Los Altos, CA (US); **Venugopal Kalluri**, San Ramon, CA (US); **Lucas E. Saule**, San Francisco, CA (US); **Peter Michaelian**, Tappan, NY (US); **Quinn Slater Huffstetler**, San Francisco, CA (US); **Charles Kirby Ambler**, San Francisco, CA (US)

(73) Assignee: **Dolby Laboratories Licensing Corporation**, San Francisco, CA (US)

(**) Term: **15 Years**

(21) Appl. No.: **29/592,696**

(22) Filed: **Feb. 1, 2017**

Related U.S. Application Data

(62) Division of application No. 29/526,417, filed on May 8, 2015, now Pat. No. Des. 780,150, which is a division of application No. 29/434,649, filed on Oct. 15, 2012, now Pat. No. Des. 731,996.

(57) **CLAIM**

The ornamental design for a telecommunications device, as shown and described.

DESCRIPTION

FIG. 1 is a top front perspective view of a telecommunications device showing our new design;

FIG. 2 is a top rear perspective view thereof;

FIG. 3 is a right side view thereof, the left side being a mirror image;

FIG. 4 is a top view thereof; and,

FIG. 5 is a front view thereof.

The broken lines illustrate structure or features that form no part of the claimed design.

The drawings include surface shading that represents contour and not surface ornamentation.

1 Claim, 3 Drawing Sheets
